LOCKET

Michael P. Patterson, Hopkins, Minn. (9201 Nicollet Ave. S., Apt. 111, Bloomington, Minn. 55436)

Original design application Feb. 29, 1972, Ser. No. 230,547, now Patent No. 227,295, dated June 12, 1973. Divided and this application Dec. 15, 1972, Ser. No. 315,327

Term of patent 14 years

Int. Cl. D11—01

U.S. Cl. D45—15

FIG. 1 is a front elevational view of a locket showing my new design;

FIG. 2 is a side elevational view;

FIG. 3 is a bottom plan view;

FIG. 4 is a sectional view taken on line 4—4 of FIG. 1; and

FIG. 5 is a rear elevational view.

This application is a division of my copending design patent application Ser. No. 230,547, filed Feb. 29, 1972, now Design No. 227,295, patented June 12, 1973.

I claim:

The ornamental design for a locket, substantially as shown and described.
